UNITED STATES PATENT OFFICE

168,597

EXPANSIBLE CHAIN FOR A BRACELET OR THE LIKE

John V. Saccione, Lodi, N. J., assignor to Drema
Manufacturing Company, Inc., a corporation of New York

Application April 7, 1952, Serial No. 19,220

Term of patent 14 years

(Cl. D45—4)

To all whom it may concern:

Be it known that I, John V. Saccione, a citizen of the United States, residing in Lodi, county of Bergen, State of New Jersey, have invented a new, original, and ornamental Design for an Expansible Chain for a Bracelet or the like, of which the following is a specification, reference being had to the accompanying drawing, forming part thereof.

Fig. 1 is a top plan view of an expansible chain for a bracelet or the like, showing my new design, conventional bottom links at the end of the chain being shown without top links, and being illustrated in broken lines, and a portion of the chain being broken away for convenience of illustration only;

Fig. 2 is a top plan view, illustrating the chain shown in Fig. 1, in an expanded position, the conventional bottom links being illustrated in broken lines;

Fig. 3 is an enlarged top plan view of a single top link; and

Figs. 4 and 5 are enlarged end and side views, respectively, of a single top link.

I claim:

The ornamental design for an expansible chain for a bracelet or the like, substantially as shown and described.

JOHN V. SACCONE.
